CLAIM

I claim the ornamental design for a standing rider golf cart, as shown and described.

DESCRIPTION

FIG. 1 is a high angle front quarter perspective view of a standing rider golf cart;

FIG. 2 is a high angle rear quarter perspective view of a standing rider golf cart;

FIG. 3 is a side elevation view of a standing rider golf cart;

FIG. 4 is a rear elevation view of a standing rider golf cart;

FIG. 5 is a front elevation view of a standing rider golf cart; and,

FIG. 6 is an overhead plan view of a standing rider golf cart. The broken line portion of the figure drawings is included to show portions of the article that form no part of the claimed design.

1 Claim, 6 Drawing Sheets(56)
